UNITED STATES PATENT OFFICE.

ERNEST CADGÉNE, OF ENGLEWOOD CLIFFS, AND GEORGE DUPONT, OF PATERSON,
NEW JERSEY.

METHOD AND MACHINE FOR DECORATING FABRICS.

Application filed May 16, 1925. Serial No. 30,652.

To all whom it may concern:

Be it known that I, ERNEST CADGÉNE, a citizen of France, residing at Englewood Cliffs, county of Bergen, and State of New Jersey, and I, GEORGE DUPONT, a citizen of the United States, residing at Paterson, county of Passaic, and State of New Jersey, have invented certain new and useful Improvements in Methods and Machines for Decorating Fabrics, of which the following is a specification.

This invention relates to improvements in the textile art, and has particular reference to a method and machine for decorating fabrics.

An object of the present invention is to implant upon a fabric, by an improved spraying operation, a decorative composition which will impart a stipple effect to the finished fabric.

Another object is to so control the spraying means with respect to its speed of operation and its position relative to the fabric to be decorated that designs having various effects may be implanted upon said fabric.

A further object is to produce a design the effect of which may be varied and repeated throughout the length of the fabric by continuously operating the spraying means and interposing between said means and the fabric a stencil through which the decorative composition is intermittently sprayed.

A still further object is to provide a spraying means wherein the spraying brush thereof may be driven at a different speed from that of the engraved roller associated therewith and wherein said speed may be varied to remove more or less of the decorative composition from said roller and spray the same upon the fabric to thereby produce varied effects thereon.

The above and other objects will appear more clearly from the following detailed description, when taken in connection with the accompanying drawings, which illustrate preferred embodiments of the inventive idea.

In the drawings—

Figure 1 is a vertical longitudinal section

through the machine constructed in accordance with the invention;

Figure 2 is an enlarged fragmentary side elevation thereof;

Figure 3 is a top plan view taken substantially on the line 3—3 of Figure 2;

Figure 4 is a fragmentary sectional view illustrating another form of the invention;

Figure 5 is a similar view showing still another form of the invention;

Figure 6 is a sectional view of still another form;

Figure 7 is a similar view of an additional embodiment; and

Figures 8, 9 and 10 are views of different engraved rollers which may be employed in connection with the invention.

Referring to the drawings and more particularly to Figures 1, 2 and 3, the numeral 11 indicates the main frame of the machine which may be of any desired construction and which is provided with an auxiliary frame 12 for supporting the spraying apparatus constituting the essential features of the invention. In the form of the invention illustrated, it is proposed to feed the fabric 13 to be decorated past the spraying apparatus by a continuous movement of said fabric and for this purpose the length of fabric is supported upon a drum 14 carried by the frame 11 and fed therefrom around the guide rollers 15 and 16 past the spraying apparatus. From thence the fabric is led upwardly into a drying chamber 17 between the heating coils 18. At the upper end of the chamber 17 the fabric is extended over a drum 19 and from thence downwardly between heating coils 20 and around the guide roller 21 to a receiving drum 22. The upper end of the drying chamber 17 is provided with an air outlet 23 in which a suction fan 24 is mounted for the purpose of exhausting the air upon the chamber 17. The drying chamber shown and described is of a well known construction and is employed merely for the purpose of drying the decorative composition which has been implanted upon the fabric by the spraying apparatus.

The spraying apparatus, which embodies the essential features of the present invention, is shown as comprising angular supporting members 25, each of the base portions of which are slidably mounted upon the top of the auxiliary frame 12 at one end thereof for movement toward and away from the fabric 13. For this purpose a screw member 26 is mounted in the frame 12 and connected to the base portion of each member 25 so that upon rotation of said screw said member 25 may be adjusted back and forth as desired. Bolts 27 are extended through a slot 28 in each member to secure the same in its adjusted positions. The upper end of each member 25 is provided with a longitudinal slot 29 in which is mounted for vertical sliding movement a bearing block 30 adjusted by means of a screw 31 carried by the member 25 and connected to said block. The bearing blocks 30 rotatably support the ends of an engraved roller 32 which may have different designs cut therein, as illustrated in Figures 8, 9 and 10.

The ends of the engraved roller 32 form bearings for a trough 33 designed to contain a color composition of any desired nature which is fed to the engraved roller preparatory to being sprayed upon the fabric 13. The ends of the trough 33 engage the ends of the roller 32 and the front wall of said trough is inclined so that its lower edge will engage the surface of the roller and combine therewith to retain the decorative composition within said trough, said lower edge acting to scrape the outer surface of the roller so that as the latter is rotated in a counterclockwise direction, as viewed in Figures 1 and 2, only so much of the composition will adhere to the roller as will fill the grooves or depressions formed therein.

Mounted for rotation in the supporting member 25 below the engraved roller 32 and adapted for contact therewith is a brush 34. This brush is rotated independently of the engraved roller and is designed to remove the composition from the roller and project the same toward the fabric 13 in the form of a spray and said composition, upon being implanted on the fabric, forms thereon a design having a stipple effect. The action of the engraved roller and the rotary brush, which is driven in a clockwise direction, is such that the dots forming the stipple design are uneven in size, as distinguished from the uniform effect produced by an air brush, and impart to the fabric the appearance of having been spattered with the composition. This stipple effect produced may be varied at will, first by varying the distance between the roller and brush and the fabric; second, by an adjustment of the engraved roller 32 to regulate the amount of contact between the same and the brush; third, by changing the viscosity of the decorative composition;

fourth, by varying the stiffness and arrangement of the bristles of the brush; fifth, by changing the speed of rotation of the brush relative to that of the roller; and sixth, by the particular engraved design on said roller.

As previously stated the roller 32 and brush 34 are independently operated so that, if desired, the speed of rotation of the brush may be varied with relation to that of the engraved roller, it being preferable to drive the brush at a much greater speed than the roller. For this purpose the stub shaft 35 at one end of the roller is extended through the frame 12 and provided upon its end 80 with a pulley 36 around which a belt 37 extends. This belt also engages another pulley 38 mounted upon the shaft 39 which carries a pulley 40 rotated by a drive belt 41 connected to any suitable source of power. 85 In a like manner one end of the brush 31 carries a pulley 42 driven by a belt 43 passing over a pulley 44 carried by a shaft 45, which also carries a pulley 46 which may be driven from a separate source of power by 90 means of the drive belt 47.

It will thus be seen that as the fabric 13 is being moved past the spraying apparatus and the roller 32 and brush 34 are being driven as described, the decorative 95 composition which adheres to any particular portion of the roller 32 after said portion has passed through the composition in the trough will be removed from the roller by the brush 34 in the form of a spray and projected on to said fabric, after which the fabric will pass through the drying chamber 17 and be wound upon the drum 22.

Referring now to Figure 4 the same construction of spraying apparatus is shown and in addition thereto there is provided a thin perforated cylindrical stencil 48, the perforations of which form a suitable design. The stencil 48 is mounted for rotation in the trunnion 49 carried by the auxiliary frame 12 and for this purpose is provided with a gear 50 meshing with a spur gear 51 driven from any suitable source of power by means of a pulley 52 and drive belt 53. The stencil 48 encloses the spraying apparatus so that said stencil will be interposed between said apparatus and the fabric 13. With this arrangement, as the composition is removed from the engraved roller in the form of a spray the same will be projected toward the interior surface of the stencil and portions of the composition will pass through the apertures in said stencil and on to the fabric as the stencil is rotated. The rotation of the stencil will thus present different portions thereof to the spray and thereby produce a varying effect in the decorative design implanted upon the fabric. The remaining portion of the composition which strikes the interior surface of the 130

stencil will flow downwardly into a trough 54 carried by the auxiliary frame 12, one wall of said trough being extended to provide a doctor blade which engages the 5 stencil.

In addition to the adjustment previously described in connection with the spraying apparatus, the form of the invention shown in Figure 4 includes an adjustment of the 10 fabric 13 toward and away from the stencil. To this end the guide rollers 55 and 56, which are the equivalent of the rollers 15 and 16, are supported by slotted brackets 57 detachably secured to the main frame of the 15 machine.

In the form of the invention shown in Figure 5 instead of utilizing a rotary stencil in connection with the spraying apparatus there is shown a perforated stencil plate 20 58 secured to the frame 12 and interposed between the spraying apparatus and the fabric. Operating in conjunction with this stencil plate is a vertically reciprocating shutter 59 slidably mounted in a guide 25 60. Reciprocation is imparted to the shutter 59 to intermittently close the apertures in the stencil plate 58 and also vary the size thereof by means of an oscillatory arm 61, one end of which is connected to the 30 lower end of the shutter 59 and the other end engaged by an eccentric 62 operated from any suitable source of power. Thus the movement of the shutter will have the same effect as the rotating stencil 48 in 35 varying the characteristics of the design being implanted on the fabric. In this form of the invention the fabric 13 may also be adjusted toward and away from the spraying apparatus, as described in connection 40 with Figure 4.

In order that compositions of various colors may be successively implanted upon different portions of the fabric as the same is moved past the spraying apparatus, a 45 plurality of such apparatus may be employed as diagrammatically illustrated in Figure 6, the apparatus in each instance being constructed in the same manner as previously described.

Instead of mounting the engraved roller above the rotary brush the positions of these elements may be reversed, as shown in Figure 7, in which instance the brush 34 may be adjusted relative to the engraved 50 roller 32 and the latter may be partially immersed in a composition contained in a trough 63 and engaged by a doctor blade 64 for removing such composition as might adhere to the outer surface of the roller.

60 What is claimed is:

1. In the textile art, the method of implanting a decorative composition upon a fabric which consists in spraying the composition toward said fabric, interposing a 65 stencil in the path of the spray, and con-

tinuously moving said stencil relative to the fabric to present different portions of the stencil to the spray to vary the characteristics of the design produced on the fabric.

2. In the textile art, the method of implanting a decorative composition upon a fabric, which consists in feeding said fabric past an engraved roller, spraying said composition from the moving roller toward said fabric and interposing between said roller and fabric a stencil through which portions of said spray will pass. 75

3. In the textile art, the method of implanting a decorative composition upon a fabric, which consists in feeding said fabric past an engraved roller, removing said composition from said roller, and in the direction of the moving fabric in the form of a spray, and interposing between said roller and fabric a stencil through which portions of 80 85 said spray will pass.

4. In the textile art, the method of implanting a decorative composition upon a fabric which consists in moving said fabric past a roller to which the composition is fed, removing said composition from said roller in the form of a spray, interposing between said roller and fabric a stencil through which portions of said spray will pass, and presenting different portions of the stencil to said spray to vary the effect produced by 90 95 said stencil during the spraying operation.

5. In the textile art, the method of implanting a decorative composition upon a fabric which consists in moving said fabric past a roller to which the composition is fed, removing said composition from said roller in the form of a spray, interposing between said roller and fabric a stencil through which portions of said spray will pass, and 100 continuously moving said stencil relative to said fabric and roller to present different portions thereof to the spray to vary the characteristics of the design implanted on the fabric. 105

6. In a textile machine, the combination of a roller to which a composition is fed, means for removing the composition from said roller and projecting the same in the form of a spray on to a fabric to produce a stipple effect thereon, and means for regulating the distance between said fabric and the first named means to vary the character of said stipple effect. 115

7. In a textile machine, the combination of a roller to which a composition is fed, means for removing the composition from said roller and projecting the same in the form of a spray on to a fabric to produce a stipple effect thereon, means to rotate said roller and removing means in opposite directions and means for effecting a relative adjustment between said roller and the first named means to vary the density of said spray. 120 125 130

8. In a textile machine, the combination of a roller to which a composition is fed, means for removing the composition from said roller and projecting the same in the 5 form of a spray on to a fabric to produce a stipple effect thereon, means for effecting a relative adjustment between said roller and the first named means to vary the density of said spray, and means for regulating 10 the distance between said first named means and fabric to alter the character of said stipple effect.
9. In a textile machine, the combination of an engraved roller to which a composition 15 is fed, means to permit said composition to remain only in the engraved portions of said roller, and means for removing said composition from said engraved portions and projecting the same on to a fabric in the 20 form of a spray.
10. In a textile machine, the combination of an engraved roller to which a composition is fed, means to permit said composition to remain only in the engraved portions of 25 said roller, and a rotary brush in contact with said roller and operable to remove said composition from said engraved portions and project the same on to a fabric in the form of a spray.
11. In a textile machine for implanting a decorative composition upon a fabric, the combination of a roller to which the composition is fed, means for removing the composition from said roller and projecting the 30 same in the form of a spray on to the fabric to produce a stipple effect thereon, a stencil interposed between said spraying means and said fabric, and means for presenting different portions of the stencil to said spray to vary the decorative effect produced by 35 said stencil during the operation of the first named means.
12. In a textile machine for implanting a decorative composition upon a fabric, the combination of a roller to which the composition is fed, a rotary brush in contact 40 with said roller and operable to remove the composition therefrom and project the same on to said fabric in the form of a spray, a stencil interposed between said brush and fabric and through which said composition is sprayed, and means for successively presenting different portions of said stencil to said spray to vary the decorative effect upon 45 the fabric during the operation of said brush.
13. In a textile machine, the combination of a roller to which a composition is fed, means for removing the composition from 50 said roller and projecting the same in the form of a spray on to a fabric to produce a stipple effect thereon, and means for independently operating said roller and spraying means to permit of the same being driven at different relative speeds.
14. In a textile machine, the combination of a roller to which a composition is fed, a rotary brush in contact with said roller and operable to remove the composition therefrom and project the same on to said 55 fabric in the form of a spray, and independent driving means for said roller and brush to permit of the same being rotated at different relative speeds.
15. In a textile machine, the combination of a roller to which a composition is fed, a rotary brush in contact with said roller and operable to remove the composition therefrom and project the same on to said fabric in the form of a spray, a rotary stencil 60 interposed between said brush and said fabric, and means for operating said roller, brush and stencil independently of one another to permit of the same being driven at different relative speeds.
16. In a textile machine, the combination of means for continuously moving a fabric, a supporting member adjustable toward and away from said fabric, a rotary engraved roller carried by said supporting member, a trough carried by said roller for containing a composition, said roller forming one of the walls of said trough, a rotary brush also carried by said supporting member and in contact with said engraved roller and operable to remove the composition from the roller and project the same toward said fabric in the form of a spray, means for rotating said engraved roller in one direction, and independent means for rotating 65 said brush in an opposite direction.
17. In a textile machine for implanting a decorative composition upon a fabric, the combination of means for projecting the composition toward the fabric in the form of a spray, a stencil interposed between said fabric and means, and means for presenting different portions of the stencil to the spray to vary the decorative effect produced upon 70 the fabric during the operation of said projecting means.
18. In a textile machine for implanting a decorative composition upon a fabric, the combination of means for projecting the composition toward the fabric in the form of a spray, a stencil interposed between said fabric and means, and means for rotating said stencil to successively present different portions thereof to the spray to vary the decorative effect produced on said fabric.
19. In a textile machine for implanting a decorative composition upon a fabric, the combination of means for projecting the composition toward the fabric in the form of a spray, a stencil interposed between said fabric and means, means for moving said fabric past said stencil in spaced relation thereto, and means for presenting different portions of said stencil to said spray as said fabric is being moved to vary the char- 75

acteristics of the design implanted upon the fabric.

20. In a textile machine for implanting a decorative composition upon a fabric, the combination of means for projecting the composition toward the fabric in the form of a spray to produce a stipple effect upon said fabric, and means for regulating the

distance between said fabric and the first named means to vary the character of said 10 stipple effect.

In testimony whereof we have affixed our signatures.

ERNEST CADGÉNE.
GEORGE DUPONT.
